POWDER DISPENSING DEVICE

Herbert La Mers, New York, and Charles Leicht,
Brooklyn, N. Y.

Application March 30, 1950, Serial No. 152,906

17 Claims. (Cl. 222—82)

1

This invention relates to a dispensing device. Broadly, it is an object of the invention to provide a device which may be readily attached to the bottom of a container of soap powder, granular, pulverulent or other similar materials to facilitate the dispensing of the contents of the container.

More particularly, it is an object of the invention to prevent the bottom of the container from becoming wet when it is placed upon a wet surface or if the surface upon which it stands becomes wet.

A further object of the device is to prevent the contents of the container from spilling if the container is accidentally pushed over.

Another object of the device is to measure the quantity of the contents of the container to be removed at any one time.

Still another object is to provide a device of the character aforesaid which can be inexpensively produced and which will be serviceable in operation and durable in use.

Another object is to provide a device of the type described which can be readily attached to a container and which will remain so attached until the contents of the container is exhausted and which can then be easily removed from the container.

Another object of a modification of the device permits the device to cut an opening in a cardboard container and become seated thereon automatically.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawings, in which:

Fig. 1 is a side elevational view of the device on a reduced scale, embodying the preferred form of the invention.

Fig. 2 is a top view of the device, the upper member being partly broken away to show the underneath structure and part of the plate directly beneath the upper member being also partly broken away to show the stop and spring member.

Fig. 3 is a section taken through line 3—3 of Fig. 2.

2

Fig. 4 is a section taken through line 4—4 of Fig. 2 showing the openings in alignment permitting the contents of the container to flow into the dispensing compartment of the device.

Fig. 5 is a longitudinal sectional view showing the lower openings of the movable portion overriding the adjacent openings of the upper or seating plate to permit continued flow of material during the dispensing period.

Fig. 6 is a partial longitudinal sectional view with a modified stop so that the openings are not in alignment upon compression of the movable portion.

Fig. 7 is a perspective view of a modified device of the same structure as the previous figures except that it contains a cutting device for piercing the bottom of a cardboard container.

Fig. 8 is an enlarged partial sectional view of the cutting device partly broken away.

Referring to the drawings, Figs. 1 to 6 inclusive, the dispensing device comprises an upper tray 10 rectangular in form having two opposed long sides 11—11, two opposed short sides 12—12 and a bottom 13. The bottom 13 has a series of regularly spaced rectangular openings 14. The four sides of the tray 10 act as a housing to receive the bottom portion of a rectangular cardboard box which may contain soap powder or other similar material. In each of the four corners on the inside of the tray 10 there are triangular shaped wedges 15 having sharp edges 16 which grip the corners 17 of the cardboard container 18 so that the cardboard container 18 cannot be dislodged from the tray 10 once it is in position therein unless the container 18 is collapsed when the contents thereof has been dispensed. It is within the realm of our invention to make a deeper tray, if desired, and to provide more than one wedge in each corner, one below the other and spaced apart from each other to provide further gripping wedges as additional holding means, if it should be found necessary depending upon the size and weight of the contents of the container 18 and the quality and thickness of the cardboard of the container 18.

The openings 14 in the bottom of the tray 10 are transverse and cover substantially the bottom 13. The bottom 13 may be removable, if desired.

The lower portion of the device comprises a rectangular housing 19 slightly less in width and in length providing a flange 20 around the lower portion of the tray 10. The lower portion has a bottom 21, opposed like sides 22, a front 23 and a back 24. Spaced a short distance from the back 24 is an upright wall 25 which runs across the width of the lower portion, that is housing 19,

and is spaced slightly more than the thickness of the movable plate 26 from the bottom 13 providing a compartment 27 at one end of the housing 19.

Plate 26 has a series of regularly spaced rectangular openings 28 of the same size as openings 14 of the bottom 13 and are adapted to coincide with openings 14 as shown in Figs. 2 and 4, that is, when the spring 29 is in expanded position. Attached to the front portion of the movable plate 26 is a drawer 30 having a compartment 31. The drawer 30 has a bottom 32 which is sloped inwardly, opposed sides 33 and a front 34. The drawer 30 has no back and communicates with the interior of the lower portion of the device. The drawer portion is adapted to move through an opening 35 in the front 23, the sides 33 and bottom 32 of the drawer 30 being sufficiently long so that they do not pass through the opening 35 when the drawer is in open or outward position as shown in Fig. 5. When the drawer 30 is in closed position the opening 35 at the front of the lower portion is sealed since the upper edge of the front wall of drawer 34 is beneath the flange 20.

Attached to the longitudinal central portion of the lower face of movable plate 26 is a central divider plate 36 which runs from the upright wall 25 to the inner edge 37 of the bottom 32 of the drawer 30 and is high enough to reach to about the bottom 21 of the lower portion of the device. Plate 36 stiffens the baffles louvres 43 and supports the drawer 30. At the end opposite the drawer 30 of movable plate 26 is a depending wall or plate 38 which serves as a finger pushing plate for the movable plate 26. The movable plate 26 slides upon a ledge 50, as shown in Fig. 5. At the back of plate 38 are inwardly projecting members 39 and lugs 40 which permit one end of the spring 29 to be seated therebetween. On the wall 25 and projecting within compartment 27 is a circular projection 41 upon which the opposite end of spring 29 is seated. Depending plate 38 stops against the inner portion of one of the short sides 12 as best shown at 42 in Figs. 4 and 5. Depending from the bottom of movable plate 26 and disposed angularly inwardly and downwardly from the back of openings 28 towards the drawer portion of the device, are a series of like baffle louvres 43 which shield the openings 28 to prevent the contents within the lower portion of the device from re-entering the container 18, especially when the contents within container 18 is low.

Along sides 22 are opposed elongated windows 44 which are divided by lines 45 which may be either painted on the windows or divided by indented lines, each division representing the equivalent of a tablespoonful of material. The opposed wall portion 22 adjacent to the pusher plate 38 between the window 44 and the back 24 are corrugated or serrated portions as shown at 45 so that the fingers get a better grip upon these portions to prevent slipping of the fingers and making it easier for the index finger to push in the plate 38. The face 47 of the projection 41 acts as a stop against the inside face of plate 38. At the four corners of the bottom 21 there are small projections or legs 49 which permits the bottom 21 of the device to be slightly raised from the surface upon which it stands.

In order to use the device heretofore described and shown in Figs. 1 to 6, inclusive, the container 18, which has been provided with perfora-

tions or scoring 49a so that a substantially large central opening 48 is provided in the bottom of the container, is seated within the tray 10, which is the upper portion of the device by pushing the cardboard container 18 inwardly, after first having removed the cardboard in the center of the container 18 providing the central opening 48. This is best accomplished by turning the container 18 upside down, removing the central portion providing opening 48, and then turning the device upside down and forcing the tray portion 10 over the cardboard walls of the container 18 which will automatically cause the wedges 15 to grip the corners of container 18. The container 18 with the device thus attached is then turned upside down so that the device becomes the bottom of the container 18. The contents, as for example the soap powder, will pass through the opening 48 of the bottom of container 18, through openings 28 falling on either side of the divider plate 36 and into the lower portion or housing 19 of the device. The lower portion will then contain five tablespoonfuls of soap powder. By tilting the container and the device and holding the same at the corrugated portion 46 between the thumb and middle finger and pressing the index finger against plate 38, the drawer 30 will thus be opened and the soap powder within the drawer will be dispensed. As the soap powder is dispensed from the drawer 30 from the lower compartment of the device, the number of tablespoonfuls being dispensed can be readily followed by watching it pass the successive lines 45 of windows 44 so that if it is desired to dispense two tablespoonfuls of powder the pressure of the index finger is released when the powder has reached the second line. The spring 29 will automatically close the drawer 30 thus cutting off the flow of soap powder. When the device and container are again set down in upright position the soap powder from the container will keep the compartment of the lower portion of the device full of soap powder so that at all times the lower portion of the device will contain five tablespoonfuls of soap powder.

In Fig. 6 a slight modification has been made in the device. The circular projection 41 is somewhat longer so that the face 47 of the projection will cause movable plate 126 to stop finger plate 138 at a point so that openings 114 and 128 are not in alignment thus preventing the soap powder from passing from the container 18 to the compartment within the lower portion 19 of the device.

It should be noted that in Fig. 5 when the drawer 30 is in open position that the openings 28 override the openings 14. This has been done with a predetermined purpose, for the following reason. When the container 18 with the device thereon is tilted and the movable plate 26 is depressed in the position shown in Fig. 5 additional soap powder will be flowing into the compartment of the lower portion while the soap powder is being dispensed so that actually more than five tablespoonfuls of powder will pass out of the drawer of the device when it is desired to dispense only five tablespoonfuls. In most instances, such as dispensing soap powder, an exact quantity is not critical and it would be to the advantage of the manufacturer who sells the powder to have a small additional percentage of the powder thus dispensed.

The divider plate 36 tends to insure an even

flow of the soap powder from the container 18 on both sides of the compartment within the lower portion and without such center plate the soap powder may flow towards one corner or side of the device and the quantity measurement will therefore not be accurate. The angle at which the louvres 43 are positioned shields the openings 14 and 23 in the bottom 13 and plate 26 respectively, preventing the contents from the compartment in the lower portion from re-entering the container while the contents are being dispensed, especially when the contents within the container 18 is low.

It is apparent that the bottom of the cardboard container 18 will be protected against water and moisture upon the floor or other surface upon which the device and container is placed since the device is water-proof and legs 49 raise the bottom of the device above the surface upon which it stands. The device may be of plastic, metal or like materials.

Referring to the Figs. 7 and 8, this modified device is substantially the device shown in Figs. 1 to 6, inclusive, except that it provides a pair of cutting units 151 imbedded in the bottom 213 and the sides 211 are higher than sides 11 since sides 211 should be slightly higher than the upper corners 156. The cutting units 151 cut openings in the bottom of the cardboard container 218 to permit the contents of the container to flow into the dispensing device. Each unit comprises a pair of like opposed triangular side walls 152 having a cutting edge 153 on the sloping edge. Fastened between side walls 152 and slightly below the cutting edges 153 and running parallel thereto is a plate 154 which has a cutting edge 155 at the top exposed edge which is curved slightly towards the upper corners 156 of the side walls 152. The fastening means may be by extending tongues 159 passing through openings in the side walls 152.

The device shown in Figs. 7 and 8 is used in the same manner as described for Figs. 1-6, inclusive. When the container 218 is turned upside down, the bottom of the container is placed between walls 211 and 212 and the device is then forced downward upon container 118 until the container reached bottom 213. This will cause the upper corners 156 of the side walls 152 to pierce the bottom of container 218. Cutting edges 153 and 155 will cut a portion 157 of the bottom of the container. Such portions 157 would lie against the angular plates 154, as shown on Fig. 7. The contents in container 218 would flow into the openings 158 provided between the side walls 152 and beneath the plate 154, thence through the openings 214 and 228 and into the compartment of the lower portion of the device. The dispensing is done in the same manner as described for Figs. 1-6, inclusive.

When the contents of the container has been dispensed the cardboard container 218 may be crushed at the corners and removed from the device. The retaining wedges 215 will release the container from the device when so collapsed.

It is obvious that various changes and modifications may be made in the details of construction and arrangement of parts without departing from the general spirit of the invention.

What we claim is:

1. A measuring and dispensing device for use with a container having a bottom opening, said device comprising an upper rectangular tray, said tray having a bottom with like openings uniformly spaced apart, wedges in the inner corners

of said tray for holding said container in firm position within said tray, a measuring chamber receptacle below said tray, a movable plate at the upper portion of said measuring chamber, said plate having like openings to coincide with the openings of the bottom of said tray, said movable plate containing a dispensing drawer at the front end thereof and a push plate at the opposite end thereof, a transverse wall across one end of said chamber, said movable plate slidable at the top of said measuring chamber and over the upper edge of said wall, said movable plate associated with the bottom of said tray and adapted to permit material from the container to enter said receptacle when the openings of said movable plate coincide with the openings of said tray bottom, said movable plate substantially cutting off communication between said container and said receptacle when said drawer is in dispensing position, spring means between said push plate and said transverse wall for automatically returning said drawer to its normal closed position.

2. The device according to claim 1 wherein said movable plate has a longitudinal central depending partition and a series of uniformly spaced baffle louvres, said baffle louvres being angularly disposed from one end of said plate openings downwardly and toward the opposite drawer end of said openings.

3. The device according to claim 1 wherein said measuring chamber has a partition at one end transversely across said chamber and running from the bottom of said chamber to slightly below the bottom of said movable plate, a stop lug for limiting the movement of said movable plate, and a spring between said partition and said movable plate for returning said movable plate to its original position.

4. The device set forth in claim 3 wherein the end wall of said measuring chamber has an opening for said dispensing drawer, transparent windows on opposed sides of the walls of said measuring chamber, said windows having uniformly spaced lines as units of measurement to visually reveal the amount of material being dispensed.

5. The device according to claim 4 wherein the upper inner walls of said measuring chamber have opposed channels upon which said movable plate rides.

6. The combination comprising a dispensing and measuring device with a container having a bottom opening, said device comprising an upper rectangular tray and a lower receptacle, said tray having a bottom with like openings uniformly spaced apart, wedges in the inner corners of said tray for holding the lower portion of said container within said tray, a movable plate at the top of said lower receptacle, a measuring chamber within said receptacle, said movable plate having like openings to coincide with the openings of the bottom of said tray, said movable plate having a dispensing drawer at the front end and a finger piece at its opposite end, a transverse wall across one end of said chamber, said movable plate slidable at the top of said measuring chamber and over the upper edge of said wall, said plate associated with said tray and adapted to permit material from said container to enter said measuring chamber when said dispensing drawer is in closed position, said movable plate substantially cutting off communication between said container and said measuring receptacle when said drawer is in dispensing position, spring means between said push plate and said transverse wall for automatically

returning said drawer to its normal closed position.

cally returning said drawer to its normal closed position.

7. The device according to claim 6 wherein the container has a closed bottom wall and the upper part of the bottom of said tray has a pair of opposed cutting units which automatically cut openings in the bottom of said container for permitting the material within said container to flow into said measuring chamber when said movable plate is in normal position, said cutting means attached to said bottom of said tray and comprising a pair of like opposed triangular side walls having cutting edges on the sloping edge thereof, a plate between said triangular side walls with a cutting edge at its top, said last-named cutting edge lower than the upper edges of said triangular side walls.

8. The device according to claim 7 wherein said cutting units comprise opposed triangular side walls, one edge of each of said side walls being a cutting edge, and an angularly disposed top wall slightly below said cutting edges and disposed between said triangular sides, said top wall having a cutting edge at the upper portion thereof, whereby when said container is pressed upon said cutting units and seated within said tray openings will be automatically cut in the bottom of said container for permitting the material therein to flow into said measuring chamber.

9. In a dispensing device, the combination of a container having a delivery opening in the bottom thereof, a tray housing adapted to fit around the lower portion of said container and to firmly grip said container over said opening in the bottom of said container, said tray housing having a bottom with like openings uniformly spaced apart, a receptacle below said tray housing, a measuring chamber within said receptacle, a movable plate slidable at the upper portion of said receptacle, said movable plate having like openings to coincide with said openings in said tray bottom, the openings of said movable plate being adapted to register with said openings of said tray bottom when the material in said receptacle is not being dispensed, a drawer at one end of said movable plate for dispensing the material from said measuring chamber when pressure is applied to said movable plate thereby moving said drawer out of said receptacle, a transverse wall across one end of said chamber, said movable plate slidable at the top of said measuring chamber and over the upper edge of said wall, spring means between said push plate and said transverse wall for automatically returning said drawer to its normal closed position.

10. In a dispensing device, the combination of a container having a delivery opening in the bottom thereof, a housing adapted to fit around the lower portion of said container firmly gripping said container over said opening in the bottom of said container, said housing having a bottom with like openings uniformly spaced apart, a measuring chamber at the lower portion of said housing, said measuring chamber having openings communicating with the interior of said container, a movable plate with like openings to coincide with said openings in said bottom, said movable plate slidable against said bottom at the upper portion of said measuring chamber and having its opening adapted to register with said openings of said bottom when the material in said measuring chamber is not being dispensed, a drawer at one end of said movable plate and a fingerpiece at the opposite end of said movable plate, a wall transversely across said measuring

5 chamber and spaced apart from said fingerpiece, a spring between said wall and said fingerpiece, whereby upon pressure of said fingerpiece, said drawer will open and dispense the material from said measuring chamber.

11. In a dispensing device, the combination of a container having a delivery opening in the bottom thereof, a tray housing adapted to fit around the lower portion of said container and to firmly grip said container over said opening in the bottom of said container, said tray housing having gripping wedges in the corners thereof for firmly gripping said container, said tray housing having a bottom with like openings uniformly spaced apart, a measuring chamber below said bottom, a movable plate having like openings to coincide with said openings in said bottom, said movable plate slidable against said tray bottom, said plate being at the top of said measuring chamber and having its openings adapted to register with said openings of said tray bottom when the material in said measuring chamber is not being dispensed and not to register when the material is being dispensed, a drawer at one end of said movable plate for dispensing the material from said measuring chamber, a fingerpiece at the opposite end of said movable plate, a transverse wall across one end of said measuring chamber spaced apart from said fingerpiece, a lug stop on said wall for limiting the movement of said fingerpiece, a spring seated upon said lug stop and against the back of said fingerpiece for returning said fingerpiece to its original position upon release of pressure thereon, whereby upon pressure upon said fingerpiece, the material within said measuring chamber will be dispensed, simultaneously shutting off the flow of material from said container to said measuring chamber, and upon release of pressure upon said fingerpiece said movable plate, drawer and fingerpiece will return to the original position causing the material from said container to fill said measuring chamber.

12. In a dispensing device, the combination of a container having a delivery opening in the bottom thereof, a tray housing adapted to fit around the lower portion of said container and to firmly grip said container over said openings in the bottom of said container, wedges in the corners of said tray housing for firmly gripping said container retaining said container within said tray housing, said tray housing having a bottom with like openings uniformly spaced apart, a measuring chamber below said tray housing, said measuring chamber having a movable plate at the upper portion thereof slidable against the tray bottom, said movable plate having like openings to coincide with said openings in said tray bottom, said openings in said tray bottom and said movable plate communicating with said container and said measuring chamber, a transverse wall below said movable plate and at one end of said measuring chamber, said movable plate slidable at the top of said measuring chamber and over the upper edge of said wall and having its openings adapted to register with said openings of said tray bottom when the material in said measuring chamber is not being dispensed and not to register when the material is being dispensed, a drawer at one end of said movable plate adapted to move out of said measuring chamber and a fingerpiece at the opposite end of said movable plate, said wall spaced a short distance from said fingerpiece, a series of baffle louvres depending from the bottom of said movable plate below each opening of said movable plate for

preventing the material from said measuring chamber from re-entering said container while the material from said measuring chamber is being dispensed, a lug stop on said wall for limiting the movement of said movable plate, a spring one end of which is seated upon said lug stop and the opposite end seated against said fingerpiece, whereby upon tilting said container with said housing and applying pressure upon said fingerpiece, said drawer will dispense material from said measuring chamber and automatically return to its original position upon release of the pressure upon said fingerpiece.

13. In a dispensing device, the combination of a container having a delivery opening in the bottom thereof, a tray housing adapted to fit around the bottom of said container and to firmly grip said container over said opening in the bottom of said container, said tray housing having a bottom with like openings uniformly spaced apart, a measuring chamber below said housing, said measuring chamber having a movable plate at the upper portion thereof, said movable plate having like openings to coincide with said openings in said tray bottom, said movable plate slidable at the top of said measuring chamber and having its openings adapted to register with said openings of said bottom when the material in said measuring chamber is not being dispensed and substantially not to register when said material is being dispensed, a drawer at one end of said movable plate adapted to move out of said measuring chamber, a fingerpiece at the opposite end of said movable plate, a transverse wall at one end of said measuring chamber spaced apart from said fingerpiece, a lug stop on said wall for limiting the movement of said movable plate, inwardly projecting lugs on said fingerpiece, a spring one end of which is seated upon said lug stop and the opposite end seated against said fingerpiece within said inwardly projecting lugs, an opening for said drawer at one end of said measuring chamber, baffle louvres depending from said movable plate and angularly disposed below the openings of said movable plate to prevent material from said measuring chamber from re-entering the container when the material is being dispensed while the container is angularly disposed, a longitudinal central wall depending from the center of said movable plate, said central wall reaching almost to the bottom of said measuring chamber to keep the material in said measuring chamber from shifting towards one end of said measuring chamber, transparent longitudinal walls at the lower portion of said measuring chamber, said transparent walls divided into uniform sections representing one tablespoonful of material, whereby upon pressure upon said fingerpiece and tilting of said container, said drawer will dispense said material and upon release of said fingerpiece, said drawer will automatically return to its original position shutting off the flow of material from said drawer and causing the material from said container to fill said measuring chamber.

14. A measuring and dispensing device for use with a container having a bottom opening, said device comprising an upper rectangular tray, said tray having a bottom with an opening, corner fastening means in said tray for holding said container in firm position within said tray, a measuring chamber receptacle below said tray, a movable plate at the upper portion of said measuring chamber, said plate having an opening to coincide with the opening of the bottom of

said tray, said movable plate containing a dispensing compartment at one end thereof and a fingerpiece at the opposite end thereof transverse wall across one end of said chamber, said movable plate slidable at the top of said measuring chamber and over the upper edge of said wall, said plate associated with the bottom of said tray and adapted to permit material from said container to enter said receptacle when the opening of said plate coincides with the opening of said tray bottom, said movable plate substantially cutting off communication between said container and said receptacle when said dispensing compartment is in dispensing position, spring means between said push plate and said transverse wall for automatically returning said drawer to said normal closed position.

15. A measuring and dispensing device for use with a container having a bottom opening, said device comprising an upper tray, said tray having a bottom with openings spaced apart, fastening means within said tray for holding said container in firm position within said tray, a measuring chamber receptacle below said tray, a movable plate at the upper portion of said measuring chamber, said plate having openings to coincide with the openings of the bottom of said tray, said movable plate containing a dispensing compartment at one end thereof and a fingerpiece at the opposite end thereof for manually moving said plate a transverse wall across one end of said chamber, said movable plate slidable at the top of said measuring chamber and over the upper edge of said wall, said plate associated with the bottom of said tray and adapted to permit material from said container to enter said receptacle when the openings of said plate coincide with the openings of said tray bottom, said movable plate substantially cutting off communication between said container and said receptacle when said dispensing compartment is in a dispensing position, spring means between said push plate and said transverse wall for automatically returning said tray to its normal closed position.

45. 16. The device according to claim 14, wherein the container has a closed bottom wall and the upper part of the bottom of said tray has cutting means which automatically cuts an opening in the bottom of said container for permitting the material within said container to flow into said measuring chamber when said movable plate is in normal position, said cutting means attached to said bottom of said tray and comprising a pair of like opposed triangular side walls having cutting edges on the sloping edge thereof, a plate between said triangular side walls with a cutting edge at its top, said last-named cutting edge lower than the upper edges of said triangular side walls.

60. 17. The device according to claim 15, wherein said measuring chamber has a central partition and a series of baffle louvers, said baffle louvers being angularly disposed from one end of said plate openings downwardly and toward said opposite dispensing compartment of said openings.
